UNITED STATES PATENT OFFICE.

JOEL T. CASE, OF NEW BRITAIN, CONNECTICUT, ASSIGNOR TO THE J. T. CASE ENGINE COMPANY, OF SAME PLACE.

DOUBLE-ACTING STEAM-ENGINE.

SPECIFICATION forming part of Letters Patent No. 394,675, dated December 18, 1888.

Application filed July 20, 1888. Serial No. 280,550. (No model.)

To all whom it may concern:

Be it known that I, JOEL T. CASE, of New Britain, in the county of Hartford and State of Connecticut, have invented certain new and useful Improvements in Double-Acting Steam-Engines; and I do hereby declare the following to be a full, clear, and exact description of the invention, such as will enable others skilled in the art to which it appertains to make and use the same.

My invention relates to an improvement in steam-engines, the object being to provide an engine which shall be composed of but few parts, simple in its construction, of great efficiency in its operation, and of comparatively small initial cost in its manufacture.

With these ends in view my invention consists, first, in a double-acting engine comprising a steam chest or cylinder casing, an oscillating cylinder located within the steam-chest, and ports for conveying the entire steam-supply for operating the engine into the opposite ends of the oscillating cylinder and ports for the exhaust of the steam into the steam-chest.

The invention further consists in a double-acting engine having an oscillating cylinder located within and supported by rounded bearings on a steam chest or cylinder casing, a sleeve attached to the oscillating cylinder and extending through an opening formed in the rounded seat of the steam-chest, the oscillating cylinder being so constructed as to form a steam-tight joint at and around the opening in the seat provided for the passage of the sleeve.

The invention further consists in a double-acting engine consisting of an oscillating cylinder provided with a reciprocating piston, the cylinder being furnished with rounded bearings, which are fitted to and supported by rounded seats formed in the steam chest or cylinder casing, and one or more steam balancing chambers or recesses located between the oscillating cylinder and its rounded seat, and serving to balance the cylinder and relieve its bearing-surfaces and its seat of undue pressure and wear.

The invention further consists in a double-acting engine comprising a steam-chest and an oscillating cylinder located and wholly

supported in the steam-chest, and ports for conveying steam to and exhaust steam from the cylinder at its sides, near its opposite ends.

The invention further consists in certain features of construction for balancing the oscillating cylinder, in certain features of construction for lubricating the crank-shaft, and in other features of construction and combinations of parts, as will be hereinafter described, and pointed out in the claims.

In the accompanying drawings, Figure 1 is a vertical longitudinal section of one form of engine embodying my invention. Fig. 2 is a vertical transverse section of the same. Fig. 3 is a view in perspective of the steam-chest with its ports and rounded bearings for the cylinder. Fig. 3^a is a section of the steam-chest, taken on a line through z z of Fig. 3. Fig. 4 is a plan view of the steam-cylinder. Fig. 5 is a vertical section of the cylinder, taken on the lines x x of Fig. 4. Fig. 6 is a vertical section taken on the line y y of Fig. 4. Fig. 7 is a view in perspective of the steam-cylinder. Fig. 8 is a plan view of the lower end of the cylinder. Fig. 9 is a vertical section of a duplex engine, and Fig. 10 is a detached view showing the relative positions of the cranks.

In the drawings, A represents the cast-iron frame or casing of the engine, which casing is cast in any desired form or shape, and may be provided with a broad and extended base for supporting the engine in a firm and steady manner. A cover or plate, A', is detachably secured to the top of the frame or casing, and plates or covers A² A³ are detachably secured to its opposite sides to provide for ready access to the crank-shaft and its bearings and the bearings of the piston-rod on the crank.

Covers A⁴ A⁵ are bolted to the opposite sides of the casing or frame near its lower end to permit of access to the inside of the casing and the working parts of the engine located therein. To the opposite sides of the casing are bolted the laterally-extended supporting-boxes B B', within which are placed the two-part bearings a a' for supporting the crank-shaft C. Set-screws b b project through the boxes B B' and serve to set up the bearings a a' to compensate for any wear thereon.

The set-crews are retained in any desired adjustment by the jam-nuts b' . To the opposite ends of the crank-shaft are keyed the fly-wheels D D, each of which has a band-wheel, 5 D', formed thereon. The crank-shaft is divided at a point within the casing, and to its adjacent ends are secured the crank-disks E E, which latter carry the crank-bearing E', through which motion is transmitted to the 10 crank-shaft.

F is the steam-chest or cylinder-casing, which is securely bolted to the frame in any desired manner. The steam-chest is formed with open ends, the faces of which are placed 15 down so as to form a steam-tight joint with the removable ends f f, which are bolted in place, and which may be readily removed whenever it is desired to gain access to the steam-cylinder located therein. Steam-chest 20 F is bored out and a cylindrical seat, G, formed therein, within which is snugly fitted the cylindrical bearing-surface h of the cylinder H, which latter has an oscillating movement within the chest, and thereby serves the 25 double purpose of a steam-cylinder and a valve for governing the admission of steam to and the exhaust from the cylinder.

I I' are steam-chambers formed within the steam-chest and at opposite sides thereof. 30 I² is an opening, which is screw-threaded for the attachment of a pipe for conveying steam to the steam-chamber I, while I³ is a screw-threaded opening communicating with steam-chamber I', and in which is secured a 35 pipe for carrying off the exhaust-steam. It is of course understood that these parts may be reversed and steam admitted to and exhausted from either one of the steam-chambers.

40 For many purposes it is necessary to provide for the reversal of the engine—as, for instance, when it is to be used in a launch or steam-yacht, (for which purpose it is admirably adapted,) and in that event a reversing-valve will be applied to the steam and exhaust pipes, so as to admit steam to either one of the steam-chambers, and thus enable the engine to be run in either direction. The steam-chamber I is provided with two ports, 45 K K'. The port K' is located at one end of the steam-chamber, while the port K is situated about midway between its opposite ends, for a purpose which will hereinafter be explained. The exhaust-chamber is provided 50 with two ports, K² K³, which are relatively arranged in the same manner as the ports K K'.

L is a steam-cylinder bored out of a metal block having flat sides L L', and a cylindrical circumference, h, which latter constitutes the 60 bearing of the cylinder within the steam-chest. Cylinder L is open at one end, while its opposite end is closed, (the bore not extending through the metal block;) and hence it will be observed that the closed ends of the block 65 constitute one end of the steam-cylinder and against which the steam acts to force the piston in one direction, while the portion m of

the steam-chest which is adjacent to the open end of the cylinder constitutes the other cylinder-head and receives the pressure of steam 70 used in driving the piston in the opposite direction.

Piston N is fitted to reciprocate within the cylinder L, and is provided with any suitable packing, n. One face, n', of the piston is 75 preferably flat, while its opposite face n² is preferably curved to conform to the curved surface m of the seat on the steam-chest, and thereby providing an intervening space between the piston and the steam-chest that 80 shall be just sufficient to hold steam enough to cushion the stroke of the piston.

N' is the piston-rod, to which the piston is detachably secured by a nut, n³, the latter being let into a recess, n⁴, formed in the end 85 of the piston. The opposite end of the piston rests against an annular shoulder, n⁵, formed on the piston-rod. A screw-threaded plug, O, is secured in an opening, O', formed in the steam-chest block, the opening O' being situated in line with the nut n³. Whenever it is 90 desired to take the engine apart for repairs or packing, the plug O is removed, and then by inserting a wrench through the opening O' the nut n³ may be unscrewed and the piston-rod disconnected from the piston and removed from the cylinder. The cylinder can 95 then be removed from its seat and the piston taken out and repacked.

P is a sleeve, one end of which is inserted 100 through an elongated opening, P', formed in the rounded seat p of the steam-chest, and is screwed into the closed end of the cylinder-block. The opening P' is of sufficient length to allow of the oscillations of the sleeve with 105 the cylinder-block, and is slightly wider than the chamber of the sleeve, so that the latter may freely move forward and backward therein. Piston-rod N' extends outward from the piston, and is encircled by and reciprocated within the sleeve P. The outer end of the piston-rod is constructed with a yoke Q, 110 within which are supported the bearing-blocks q q', between which is journaled the crank E'. The bearing-blocks may be readily adjusted to compensate for wear by means of the wedge Q' and nuts Q², which parts are 115 accessible through the openings closed by the removable cover A² A³, attached to the opposite sides of the casing.

The outer end of sleeve P is provided with a stuffing-box, P², which serves to form a steam-tight joint between the sleeve and piston-rod and prevent the escape of steam from the steam-cylinder. By the employment of 120 the stuffing-box on the end of the sleeve the piston-rod may be allowed to move freely within the sleeve and be subjected to little or no frictional contact therewith, and thereby allow of the use of a long sleeve which in its 125 operation constitutes a long lever for oscillating the cylinder-block within the steam-chest.

At the open end of the cylinder the side

walls are cut away, as shown, so as to form straight walls R R', which move over the ports K' K³, through which steam is admitted and exhausted from the open end of the steam-cylinder. At the opposite sides of the closed end of the cylinder are located the steam-port R and exhaust-port R'. These ports are so constructed that their lower walls are preferably on the same horizontal plane as the inner 5 face of the lower and closed end of the cylinder. Ports R R' connect with rectangular recesses S S', formed in the circumference of the cylinder-block. Recesses S S' form passages which connect the ports K and K² with 10 the ports R and R'.

The sides of the cylinder are rabbeted at their edges, and within such grooves are placed rings r r, made of gun metal or other suitable material, which has a greater coefficient 20 of expansion than cast-iron. On the admission of steam to the engine the packing-rings will expand sufficiently to relieve the cylinder of any undue friction or wear, and yet form packing to prevent the escape 25 or leakage of steam.

The operation of the engine may be briefly described as follows: The piston having reached the limit of its outward stroke and just commenced to return, steam will be admitted 30 through the port K' to the open end of the steam-cylinder, the exhaust-port K³ being closed, while the steam-port K at the other end will be closed and the exhaust-port K² open. Steam will then act against the outer 35 face of the piston and force it to the opposite end of the cylinder. The oscillation of the cylinder-block will close steam-port K' and exhaust-port K², and open steam-port K and exhaust-port K³, and thus admit steam between 40 the inner face of the piston and the closed end of the cylinder, and thereby drive the piston through its outward stroke. I have already called attention to the fact that the ports K K² are situated about midway between 45 the opposite ends of the cylinder, and that steam is admitted to and exhausted from the inner end of the cylinder (and by inner end I mean the end nearest the crank-shaft) through recesses S S' in the opposite sides of 50 the cylinder-block, which connect with the ports R R' at the extreme inner end of the cylinder. The object of this construction and arrangement of parts is twofold—viz., to furnish an extended bearing-surface to the 55 cylinder-block on its seat around and adjacent to the opening P' provided for the sleeve, and thereby insure a steam-tight joint at this point throughout the entire range of movement of the cylinder-block. It will be observed 60 that the cylinder-block has a curved bearing extending from the port R to the port R', which forms a steam-tight joint around all sides of the opening P' throughout every adjustment of the cylinder-block in the operation 65 of the engine, and hence effectually prevents any escape of steam through the opening P'. Another object of

this construction is to provide for the steam balancing of the oscillating piston-block in the operation of the engine. This is a most 70 important feature in the practical operation of the engine. I accomplish this feature of my invention by so arranging the ports as to insure an extended bearing between the inner end or surface of the cylinder-block and 75 its seat, and form two steam channels or chambers, T T, in such curved surface or bearing on the cylinder-block, each channel or chamber communicating at its opposite ends with and receiving steam from the 80 steam-ports K K². The channels T T are of such area that, in connection with the area of the steam-recesses formed in the bearing-surface of the cylinder-block, the total balancing area shall be equal to the area of the 85 piston, and hence insure a perfect balancing of the cylinder-block when in operation. In this way I reduce the wear and friction of the parts to a minimum, and am enabled to produce an engine in which the steam-cylinder 90 performs, in addition to its ordinary function, the function of a valve for governing and controlling the admission and exhaust of steam, whereby I am enabled to dispense with the separate valve and valve-motion ordinarily employed. Owing to the perfect 95 balancing of the cylinder-block, it oscillates in its steam-chest and performs the function of a valve by a very small expenditure of power, and is subjected to an almost inappreciable amount of friction or wear.

The following provision is made for lubricating the crank-shaft of the engine: The casing in which the crank-shaft is located is filled with oil or lubricating material up to 105 about the center of the wrist-pin of the crank-shaft when the latter is in its downward position, and hence the crank in its revolution will pass through the body of lubricating material. To one of the crank-disks is secured 110 an inclined ledge or shelf, U, which serves to elevate a certain quantity of oil and to cause its discharge laterally toward the inner wall of the casing. A cup or other suitable receptacle, U', is secured to or formed on the casing, and serves as a receptacle for the oil discharged by the crank-disk. From the receptacle U the oil flows through an inclined duct or channel, U', formed in the upper surface of the bearing u. A portion of the oil so discharged flows through the oil-duets formed in the bearing and onto the crank-shaft, while such portion as escapes at the end of the bearing falls onto the crank-shaft and is removed therefrom by the wiper u', which consists of 120 a thin sheet-metal spring fastened at one end to the bracket-collar, the free end of the spring being arranged to rest upon the shaft and remove all excess of oil therefrom. This excess is discharged into the escape-channel u², from 125 which it escapes into the body of oil in the reservoir.

Figs. 9 and 10 represent a duplex double-acting engine embodying my invention. In

this form of engine the steam-chest is exactly of the same construction as in a single-cylinder engine, excepting that it is double the length, so as to accommodate two oscillating cylinder-blocks instead of one. The two cylinder-blocks are placed side by side, and a ring, t' , formed of gun-metal or other suitable metal or alloy, is let into grooves t^2 t^2 , formed in the adjacent faces of the cylinder-blocks. 5 The metal or alloy of which this ring is made has a greater coefficient of expansion than cast-iron, and hence when steam is admitted to the engine the ring t' will be expanded, so as to relieve the oscillating cylinder-blocks of any undue friction, but at the same time form a steam-tight joint between the ring and the bearing-surface of the steam-chest, and thereby prevent the escape of steam past one cylinder-block to the other and adjacent one. In 10 this form of engine the crank is made double, one crank being located slightly at one side of a vertical line which cuts the center of the crank-shaft and the other crank. Thus the two cranks are so located as to obviate a dead-center, and still to cause the two pistons to transmit power in opposite directions to the crank-shaft, and thus subject the bearings of the latter to the least possible pressure and wear. 15

It is evident that many changes might be made in the form of construction and relative arrangement of the parts of my improved engine without departing from the spirit or scope of my invention. The engine frame or 20 casing and the other parts may be constructed so that the engine may be used either as an upright engine, as shown in the drawings; or the engine may be constructed to be suspended from a ceiling, or may be constructed so as to be supported midway of its casing. Other 25 changes might be made; and hence I do not restrict myself to the particular construction and arrangement of parts shown and described; but

Having fully described my invention, what I claim as new, and desire to secure by Letters Patent, is—

1. In a double-acting steam-engine, the combination, with a steam-chest and oscillating cylinder, each provided with ports whereby steam is admitted to and exhausted from the opposite ends of the cylinder by the oscillatory movement of the cylinder, of one or more steam balancing-chambers located between the oscillating cylinder and its rounded seat, substantially as set forth. 30
2. In a double-acting engine, the combination, with a steam-chest and oscillating cylinder, each provided with ports whereby steam is admitted to and exhausted from the opposite ends of the cylinder by the oscillatory movement of the cylinder, of one or more steam balancing-chambers located between 35

the oscillating cylinder and its rounded seat adjacent to the opening in the steam-chest 65 provided for the piston-rod and sleeve, substantially as set forth.

3. In a double-acting engine, the combination, with a steam-chest and oscillating cylinder, the latter constructed with a closed end or head at one end and open at its opposite end, of ports in the steam-chest and oscillating cylinder, whereby steam is admitted to and exhausted from the opposite ends of the cylinder by the oscillating movement of the 70 cylinder, and one or more steam balancing-chambers located between the closed end of the cylinder and its rounded seat, substantially as set forth.

4. In a double-acting steam-engine, the combination, with an oscillating cylinder having a head at one end and open at its opposite end, of a steam-chest having ports adapted to communicate with the open end of the cylinder, and ports in the steam-chest communicating with steam-passages in the cylinder which lead to the closed end of the cylinder, said ports being so arranged that the admission and exhaust of steam are controlled by the oscillatory movement of the cylinder, substantially as set forth. 80

5. In a double-acting engine, the combination, with a steam-chest and an oscillating cylinder, the latter inclosed within the steam-chest and wholly supported by the cylindrical seat in the steam-chest, of ports in the steam-chest and cylinder, whereby steam is admitted to and exhausted from the opposite ends of the cylinder by the oscillatory movement of the latter, and one or more steam 85 balancing-chambers located between the oscillating cylinder and its rounded bearing or seat, substantially as set forth. 90

6. In a double-acting engine, the combination, with a steam-chest provided with a cylindrical bearing or seat, of an oscillating cylinder fitted to and wholly supported by said cylindrical bearing or seat, and provided with flat sides which engage the sides of the steam-chest, substantially as set forth. 100

7. In a double-acting engine, the combination, with a steam-chest and an oscillating cylinder inclosed within and wholly supported by the cylindrical seat in the steam-chest, of gun-metal or equivalent rings fitted into grooves formed in the sides and periphery of the cylinder, whereby said rings steam-pack the cylinder around its periphery and at its sides, substantially as set forth. 115

In testimony whereof I have signed this 120 specification in the presence of two subscribing witnesses.

JOEL T. CASE.
